SAFETY RAZOR

George T. Turner, Radford, Va.

Application August 6, 1934, Serial No. 738,716

9 Claims. (Cl. 30—53)

My invention relates generally to safety razors, and particularly to a safety razor in which the cutting plane of the blade may be arranged in longitudinal extension of the plane or parallel 5 to the plane of the handle, or approximately at right angles to the plane of the handle, according to the preference of the user, and an important object of my invention is to provide a razor of the character indicated having a blade holder 10 which by reason of its formation and manner of connection to the handle is suitable for either four-edged blades or double edged blades.

An important object of my invention is to provide a razor of the type indicated above which 15 is simple and inexpensive in construction, easily adjusted and manipulated, and incapable of getting out of order except through breakage.

Other objects and advantages of my invention will be apparent from a reading of the following 20 description in connection with the drawings, wherein for purposes of illustration I have shown preferred embodiments of my invention.

In the drawings:—

Figure 1 is a top plan view of an embodiment 25 having a blade holder equipped to hold a four-edged blade.

Figure 2 is a side elevational view of Figure 1.

Figure 3 is a transverse vertical sectional view 30 taken through Figure 2 approximately on the line 3—3 and looking toward the right in the direction of the arrows.

Figure 4 is a plan view of the four-edged blade.

Figure 5 is a side elevational view of this embodiment showing the blade holder arranged on 35 the handle as in a hoe-type safety razor.

Figure 6 is a vertical transverse sectional view through Figure 5.

Figure 7 is a plan view of the blade guard.

Figure 8 is a plan view of the bottom of the cap.

Figure 9 is a plan view of a double edged blade.

Figure 10 is a guard for the double edged blade.

Figure 11 is the cap for the double edged blade.

Referring in detail to the drawings, the numeral 5 refers generally to the handle of the 45 razor which handle comprises a rectangular portion 6 having near one end the reduced part 7 and provided at its opposite end with a shoulder 8 from which longitudinally extends the reduced squared portion 9 which at its extremity has a 50 further reduced portion 10 which is threaded as indicated at 11. The handle is composed of two half-sections pivoted together by a rivet or bolt 8' so that when closed together the half-sections are in superposed relation and resist being forced 55 apart in a direction parallel to the axis of the pivot 8'.

Adapted for use with this handle 5 is a four-edged blade head generally designated 13 and/or the double-edged blade head 14.

60 The four-edged blade head 13 comprises the

guard generally designated 15 which is square as shown in Figure 7 and provided for the greater part of the length of its side edges with notches 16 in a manner well known in the art. The guard plate 15 has a central hole 17 to pass the reduced portion 10 of the handle 5 when the handle is attached to the blade holder in hoe-handle fashion as shown in Figures 5 and 6. Radially spaced from the opening 17 and extending parallel to the side edges and at right angles from the underside of the plate 15 are slots 18', 19', 20' and 21' which accommodate the loops 18, 19, 20, 21 which depend from the bottom of the cap 24 at such a distance that when the handle is placed through two diametrically opposite loops as shown in Figures 2 and 3, the flat side of the reduced portion 9 will frictionally engage the underside of the plate 15, and the half-sections of the part 9 will grip the bight portions of the engaged loops, and the shoulder 8 will engage the adjacent edge of the 20 plate 15 as indicated in Figure 2. By this arrangement the cutting plane of the blade which is generally designated 22 will be in extension of 25 or parallel to the plane of the handle 5. It is obvious that by withdrawing the handle 5 from the head 13 and replacing the part 9 of the handle in engagement with the two remaining diametrically opposed loops 19, 21, instead of the loops 18 and 20 which are shown in Figure 2, two 30 opposite and different edges of the four-edged blade 22 will be placed in shaving position. Thus, simply by pulling the head from the handle and reinserting the handle in the other loops two different opposed shaving edges may be availed of.

When it is desired to attach the handle to the head 13 in hoe-handle fashion, the threaded portion 11 is passed through the opening 17 in the guard plate 15 and engaged in the threaded opening 23 in the cap 24 which has its underside slightly concaved as indicated at 25 to properly hold 40 the blade 22 on the convex upper side of the plate 15 as shown in Figures 3 and 6. The loops 18, 20, and 19, 21, respectively, pass through the corresponding slots 18', 20' and 19', 21', respectively of the guard plate 15 so as to accurately position 45 the cap and the blade and the guard 15, the blade 22 being provided with corresponding slots 18a, 20a and 19a and 21a, respectively, and the central opening 27.

The double-edged blade head generally designated 14 in Figure 6 comprises a guard 28 which has the slotted opposite edges as indicated at 29 and is of generally elongated form to conformably receive the blade 30 which is held in place by the cap 31 which has two longitudinally spaced loops 32, 33, respectively, arranged to pass through registering slots 34, 35 in the blade, and other registering slots 36, 37 in the guard 28. The reduced portion 10 of the handle 5 is passed 55 through the central opening 38 in the guard, the 60

central opening 39 in the blade, and engaged with the threaded portion 11 in the threaded hole 14 in the cap 31; or the squared part 9 of the handle is pushed through the loops 32, 33 to connect the head 14 to the handle in much the same manner as indicated in Figure 2 in connection with the four-edged blade holder.

Although I have shown and described herein a preferred embodiment of my invention, it is to be definitely understood that I do not desire to limit the application of the invention thereto, and any change or changes may be made in materials and in structure and arrangement of parts, within the spirit of the invention and the scope of the 15 subjoined claims.

If desired, the lower section of the handle appearing in Figure 2 of the drawings may be swung on the pivot 8' relative to the upper section of the handle to a position similar to that given the 20 handle of a straight or duplex razor relative to the blade part while shaving therewith.

What is claimed is:—

1. A safety razor of the character described comprising a cap having members extending 25 therefrom, a razor blade, a guard, said members traversing the blade and the guard and extending outwardly from one side of the guard, and a handle having a first part insertable between certain 30 of said members and the said side of the guard for connecting the handle thereto, said handle including a second part engaged with the outer side of said members opposite said first part.

2. A safety razor of the character described comprising a cap, a blade, and a guard, and a 35 handle having a split extremity providing a pair of relatively movable sections each including a threaded portion, said extremity traversing said guard and said blade and said threaded portions being engaged in a threaded opening in said cap, 40 said cap having bails traversing the blade and the guard for aligning the cap, the blade, and the guard with respect to each other.

3. A safety razor of the character described including a four-edged blade, a guard engaging one 45 side of the blade, a cap engaging the opposite side of the blade, said cap having bails traversing the blade and the guard, said bails being arranged in diametrically opposite pairs, and a handle selectively inserted between portions of a pair of bails 50 and one side of the guard for connecting the handle so as to position said blade in a plane substantially parallel with the axis of the handle.

4. A safety razor comprising a head composed 55 of a guard, a blade resting on the guard, a cap lying on and holding said blade in place on the guard, said cap having at least two loops traversing said blade and said guard and projecting from the outer side of the guard, and a handle having a first part slidably inserted through a pair of said loops so as to be frictionally engaged with said 60 outer side of the guard and with the inner sides of the loop so as to hold said cap, said blade, and said guard in assembled condition, said handle further including a second part slidably engaged with the outer side of the loops.

5. A safety razor comprising a head composed 65 of a guard, a blade resting on the guard, a cap lying on and holding said blade in place on the guard, said cap having at least two loops traversing said blade and said guard and projecting from

the outer side of the guard, and a handle having a first part slidably inserted through a pair of said loops so as to be frictionally engaged with said outer side of the guard and with the inner sides of the loops so as to hold said cap, said blade, and said guard in assembled condition, said handle further including a second part pivotally connected to the said first part and arranged to be moved relative to said first part so as to frictionally engage the outer sides of said loops in 10 opposition to said first part.

6. A safety razor comprising a head composed of a guard, a blade resting on the guard, a cap lying on and holding said blade in place on the guard, said cap having loops traversing said blade and said guard and projecting from the outer side of the guard, and a handle having a part slidably insertable through a pair of said loops so as to be frictionally engaged with said outer side of the guard and hold said cap, said blade, and said guard in assembled condition, said part of the handle being composed of a pair of longitudinally divided sections, one of which is arranged to pass through said loops and engage said outer side of the guard while the remaining section 25 frictionally engages the outer side of said loops, said sections being pivotally connected, the pivotal connection of said sections lying outwardly of the head of the razor and permitting laterally swinging said remaining section out of and into operative engagement with said outer side of said loops in cooperative relation with said one section.

7. A safety razor comprising a head composed of a guard, a blade lying on said guard, a cap lying on said blade and holding the same in place, and a handle having a threaded part traversing said guard and said blade and engaged with a threaded opening provided in said cap, said cap having more than two bails traversing relatively long transverse slots formed in said blade and said 40 guard and projecting from the outer side of said guard, said bails and long slots facilitating assembling and aligning of the cap, blade and guard.

8. A safety razor comprising a head composed of a guard, a blade lying on said guard, a cap lying on said blade and holding the same in place, and a handle having a threaded part traversing said guard and said blade and engaged with a threaded opening provided in said cap, said cap having means traversing said blade and said guard for aligning the cap, blade and guard, said threaded part of the handle being composed of a pair of longitudinally divided sections arranged to compress toward each other when the handle is threaded in place.

9. A safety razor comprising a head composed of a guard, a blade lying on said guard, a cap lying on said blade and holding the same in place, and a handle having a threaded part traversing said guard and said blade and engaged with a threaded opening provided in said cap, said cap having means traversing said blade and said guard for aligning the cap, blade and guard, said threaded part of the handle being composed of a pair of longitudinally divided sections connected together at their axially outward ends only, the inner ends of said sections being compressed toward each other when threaded in place.
